[57] CLAIM

The ornamental design for decorative panel for a chandelier, as shown and described.

DESCRIPTION

FIG. 1 is a perspective view of decorative panel for a chandelier showing my present design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view; and,

FIG. 8 is an elevational view showing the decorative panel in use, the chandelier being shown in broken lines for illustrative purposes only, and forming no part of the claimed design.
